(57) **CLAIM**

The ornamental design for a combined bushing extractor with a receiving cylinder, as shown and described.

DESCRIPTION

FIG. 1 is a top front-right hand side perspective view of a bushing extractor showing a receiving cylinder portion in assembly with a rail guide assemblage portion;

FIG. 2 is a top front-right hand side perspective view of the rail guide assemblage portion without the cylinder portion; FIG. 3 is a bottom rear-left hand side perspective view of FIG. 2;

FIG. 4 is a top rear-left hand side perspective view of FIG. 2;

FIG. 5 is a bottom front-right hand side perspective view of FIG. 2;

FIG. 6 is a bottom front-left hand side perspective view of FIG. 2;

FIG. 7 is a front view of FIG. 2;

FIG. 8 is a rear view of FIG. 2;

FIG. 9 is a left-hand side view of FIG. 2, wherein a right-hand side view is a mirror image of the left-hand side view;

FIG. 10 is a top view of FIG. 2;

FIG. 11 is a bottom view of FIG. 2;

FIG. 12 is a perspective view of the receiving cylinder portion;

FIG. 13 is a front view of FIG. 12;

FIG. 14 is a rear view of FIG. 12;

FIG. 15 is a left-hand side view of FIG. 12, wherein a right-hand side view is a mirror image of the left-hand side view; and,

FIG. 16 is a top view of FIG. 12, wherein a bottom view is a mirror image of the top view.
